UNITED STATES PATENT OFFICE.

MILTON O. REEVES, OF COLUMBUS, INDIANA, ASSIGNOR TO REEVES PULLEY COMPANY, OF COLUMBUS, INDIANA, A CORPORATION OF INDIANA.

SPEED-VARYING MECHANISM.

SPECIFICATION forming part of Letters Patent No. 785,917, dated March 28, 1905.

Application filed December 21, 1903. Serial No. 186,121.

To all whom it may concern:

Be it known that I, MILTON O. REEVES, a citizen of the United States, residing at Columbus, in the county of Bartholomew and State of Indiana, have invented certain new and useful Improvements in Speed-Varying Mechanisms, of which the following is a specification.

In speed-varying mechanisms of the type shown in Patent No. 603,067, issued April 26, 1898, to the Reeves Pulley Company, the action of the V-shaped belt upon the cone-shaped disks is like the successive driving introduction of a plurality of wedges between the disks, and as a consequence the thrust exerted by the disks upon the bearings controlled by the shifting lever is considerable.

The object of my present invention is to produce a construction which will automatically during normal operation substantially entirely withdraw the thrust from said bearings and cause the two disks to interact one upon another and place all or substantially all of the stress upon themselves and their connections.

The accompanying drawings illustrate my invention.

Figure 1 is a plan with the driving-belt shown in section; Fig. 2, an enlarged elevation of one pair of disks; Fig. 3, a perspective view of a detail, and Fig. 4 an axial section of a modified form.

In the drawings, 10 indicates the driving-shaft, which is to be rotated at a constant speed, and 11 indicates the driven shaft, which is to be rotated at a varying speed. Rotatably mounted upon shaft 10 is a pair of disks 12 12, each of which is provided on the periphery of its hub with a spiral groove or thread 13. Secured to shaft 10 between the two disks 12 is a collar 14, provided with a plurality of oppositely-projecting pins 15, which are parallel with the shaft and which project through suitable slots 16, formed in the disks 12 at a point below the lowest operating-point of a usual V-shaped driving-belt 17. Each of the pins 15 carries on each of its ends a head 15', within which is pivoted upon an axis 15"

at right angles to the axis of shaft 11 a shoe 15", which shoe fits the adjacent groove or 50 thread 13. The grooves 13 are so arranged that when a driving impulse is given to shaft 10 in the direction indicated by the arrow on collar 14 and the disks 12 are held stationary shoes 15" will slide within grooves or threads 55 13 and draw the disks 12 together axially upon shaft 10. Similarly shaft 11 has rotatably mounted upon it a pair of driven disks 18 18, the hub of each of which is provided with a groove or thread 19, the inclination of 60 said threads being exactly opposite to the inclination of threads 13. Shaft 11 carries a collar 20 between the two disks 18, which collar carries oppositely-extending arms 21, each having at each end a head 22, within which 65 is pivoted the shank of a shoe like shoe 15", mounted in the adjacent groove or thread 19, the arms 21 passing through slots 23 in the disks 18. Each of the disks is provided at the outer end of its hub with a suitable thrust-bearing 25, each of which takes against a yoke 26, and these yokes are connected by two shifting levers 27 27 in a manner well known in 70 this type of machine.

In operation with the parts in the position 75 shown in Fig. 1, suppose shaft 10 be rotated, collar 14 will be driven in the direction indicated by the arrow, and pins 16 will be also revolved about the shaft 11, and shoes 15" will slide in grooves 13, and thus tend to draw 80 the two disks 12 together. This tendency, however, will be resisted by the belt 17, and consequently the shoes 15" serve to drive the disks 12 in the same direction as shaft 10, also driving belt 17 in the same direction. 85 The belt 17 thereupon acts upon the disks 18, which being driven in the direction indicated by the arrow slide grooves 19 beneath the shoes therein, thus tending to draw disks 18 together, this tendency being resisted by the 90 transverse resistance of the belt 17, and thereby causing a rotation of shaft 11. As a consequence the wedging force of the belt is resisted by the consequent tendency of the disks to draw together, so that the thrust is taken 95 away from the bearings 25, and there is a less

thrust upon these bearings except at the time when levers 27 are swung, so as to shift the two pairs of disks upon their shafts. When this takes place, the disks will have a rotation 5 upon their shafts.

In Fig. 4 I show a modification. Here the central collar of the shaft is dispensed with, as are the oppositely-extending arms, the shoes, &c., and instead the bore of the hub of the disk 10 is provided with a thread 30, which receives a thread-key 31.

I claim as my invention—

1. In a speed-varying mechanism of the type described, the combination with a shaft, 15 and a pair of cone-shaped driving-disks mounted thereon and both axially and angularly movable relatively thereto, of a driving connection between the shaft and disk capable of relative angular displacement, whereby relative angular displacement between the disks and shaft will cause opposite axial movement of the two disks upon the shaft.

2. In a speed-varying mechanism of the type described, the combination, with a pair 25 of parallel shafts, of two pairs of cone-shaped driving-disks one pair mounted upon each of said shafts, an intermediate driving connection between the driven shaft and its pair of disks tending upon forward rotation of said 30 driving-shaft to angularly displace the shaft within the disks and consequently draw the

disks together, a driving connection between the driven disks and the driven shaft tending upon driving of the driven disks to displace said driven disks upon the driven shaft angularly and consequently to draw the driven disks together, and a belt running between the two pairs of disks. 35

3. In a speed-varying mechanism, the combination, with a shaft and a pair of cone-shaped driving-disks sleeved thereon, and having a pair of oppositely-arranged screw-threads one formed on each of the disks, and a pair of shoes carried by the shaft and mounted one in each of said threads, for the purpose 40 set forth. 45

4. In a speed-varying mechanism, the combination, with a shaft, and a pair of cone-shaped driving-disks sleeved thereon and each having a thread 13, and a belt running between said disks, of a collar carried by the shaft between the disks, arms carried by the collar and extending through the disks, and a shoe carried by each arm and engaging the adjacent thread, for the purpose set forth. 50 55

In witness whereof I have hereunto set my hand and seal, at Columbus, Indiana, this 7th day of December, A. D. 1903.

MILTON O. REEVES. [L. S.]
